UNITED STATES PATENT OFFICE.

FRITZ HOLLAND, OF NEW YORK, N. Y., ASSIGNOR, BY MESNE ASSIGNMENTS, TO BRAINCRAFT COMPANY, INCORPORATED, OF NEW YORK, N. Y., A COMPANY OF NEW YORK.

METHOD OF MANUFACTURING SHOES WITH ADHESIVELY-ATTACHED SOLES.

Application filed August 17, 1928. Serial No. 300,286.

My invention relates to improvements in methods of manufacturing shoes with adhesively attached soles, and the object of the invention is to devise a method which will 5 enable soles to be cemented to the tapes secured to the lower marginal edge of uppers in the case where the last employed has its lower surface arched for use in manufacturing a shoe with a heel in contradistinction to 10 a last with a flat lower surface used in the manufacture of shoes or slippers without heels.

Hitherto in manufacturing shoes and slippers with cemented on outer soles, a method 15 has been evolved and is used extensively wherein the lower marginal edge of the upper is not inturned, but is replaced by a flexible inturned tape with a draw string. In the manufacture of flat soled shoes and 20 slippers this is an eminently satisfactory and economical method where the shoe is made to fit both the right or left foot as the tape can be drawn tight by the draw string and does not pucker as does the less flexible up- 25 per when inturned. The above method is not, however, susceptible to use in the manufacture of shoes with arched soles wherein a shank is inserted, for the reason that in drawing the tape taut over a last with an arched lower surface or sole portion, the tape 30 will gape at such arched portion and will not lie close to the last. Such being the case, it is impossible to cement the sole satisfactorily to the tape.

35 By my method such disadvantage is overcome and the outer sole can be firmly secured to the tape as such tape will lie snugly against the last. Consequently the finished shoe will conform identically to the shape 40 of such last.

Even in the case of a shoe with a flat sole manufactured to fit either a right or a left foot the existing method above described 45 can not be used as the tape will gape from the last on the inner side of the shoe whereas by my method this disadvantage is overcome.

In carrying out my method I provide 50 means for securing the tape to the shoe shank usually employed in shoes with arched soles at that part of the shank which is in the vicinity of the arched portion of the shoe. This will hold the tape in snugly against the last and will not allow it to

gape. In the manufacture of flat sole shoes 55 I provide a shank which is not ordinarily used with the tape method.

Referring to the drawings:—

Fig. 1 represents an inverted plan view 60 of the last showing the upper provided with the tape in place and the shank inserted between the tape and sole portions of the last.

Fig. 2 is a side elevation of an inverted 65 last showing the upper thereon and the shank in section.

Fig. 3 is a fragmentary cross section of a last showing the upper and shank in place and the means for attaching the tape on the upper to the shank initially.

Fig. 4 is a similar view to Fig. 3 showing 70 the final step in my method.

Fig. 5 is a plan view of a shoe shank provided with my tape securing means, and

Fig. 6 is an enlarged cross sectional view 75 thereof.

Like characters of reference indicate corresponding parts in the different views.

1 is the shoe last with the arched lower surface on sole portion 2. 3 is the shoe upper provided along its lower marginal 80 edge with a flexible tape 4 which contains a draw string 5, such upper preferably terminating at the margin of the sole portion 2 of the last, and the tape being inturned to lie along the sole 2 of the last.

85 6 is the shoe shank which may be constituted, in the usual manner, of any material or combination of materials, and provided with a plurality of transversely disposed staples 7 which, when the shank is in place, 90 are situated in the vicinity of the arched part of the sole portion 2 of the last.

The staples 7 are preferably inserted into the shank 6 before such shank is put in place during the lasting operation, and the tines 95 of the staples initially extend at substantially right angles to the surface of the shank.

In carrying out the lasting operation I first apply the upper 3 to the last 1 and pull the ends of the draw string 5 contained in 100 the tape 4 so that the tape is reasonably taut, and wherein it will assume the position illustrated in dotted lines in Figure 2.

I then insert the shank 6 in position between the tape 4 and the sole portion 2 of 105 the last with the tines of the staples 7 so disposed that they extend outwardly.

I then press in the gaping portions of the

tape 4 and insert the tines of the staples 7 thereinto as shown in Fig. 3. Subsequently, I pull again on the draw string 5 which draws the tape 4 taut throughout its length 5 and secure the ends of the draw string, and finally cleat down the tines of the staples 7.

The shoe is then ready to have the outer soles cemented to the upper.

From the above description it will be apparent that I have devised a method which will enable tapes on the marginal lower edge of uppers used in the manufacture of flat sole shoes and slippers with cemented on soles to be employed in the manufacture of 15 arched sole shoes with adhesively attached outer soles, or flat sole shoes manufactured for either the right or left foot with adhesively attached soles.

By my method, in addition, the appearance 20 of this class of footwear will be greatly improved and, moreover, the sole will be more firmly secured to the upper.

What I claim as my invention is:

1. In a method of manufacturing shoes 25 with adhesively attached outer soles, the steps, in the lasting operation, which consist in applying an upper provided with a flexible tape extending round its lower marginal edge to a last, drawing the tape 30 taut, then inserting a shoe shank between the tape and last, and subsequently pressing inwardly the portions of the tape which gape from the last, and securing such portions to the shank.
- 35 2. In a method of manufacturing shoes with adhesively attached outer soles, the steps, in the lasting operation, which consist in applying an upper provided with a flexible tape extending round its lower marginal

edge to a last having an arched sole portion, 40 drawing the tape taut, then inserting a shoe shank between the tape and last, and subsequently pressing inwardly the portions of the tape which gape from the last in the vicinity of the arched part of the last and 45 securing such portions to the shank.

3. In a method of manufacturing shoes with adhesively attached outer soles, the steps, in the lasting operation, which consist in applying an upper provided with a flexible 50 tape extending round its lower marginal edge to a last, drawing the tape taut, then inserting between the tape and last a shoe shank having outwardly directed tape securing elements, subsequently pressing inwardly 55 the portions of the tape which gape from the last, hooking said tape portions over the outwardly directed tape securing elements, and finally cleating down such tape securing elements. 60

4. In a method of manufacturing shoes with adhesively attached outer soles, the steps, in the lasting operation, which consist in applying an upper provided with a flexible 65 tape extending round its lower marginal edge to a last having an arched sole portion, drawing the tape taut, then inserting between the tape and last a shoe shank having outwardly directed tape securing elements, subsequently pressing inwardly the portions 70 of the tape which gape from the last in the vicinity of the arched part of the last, hooking said tape portions over the outwardly directed tape securing elements, and finally 75 cleating down such tape securing elements.

In testimony whereof I affix my signature.

FRITZ HOLLAND.
